UNITED STATES PATENT OFFICE.

FRANCIS P. BOLAND, OF PROVIDENCE, RHODE ISLAND.

SAND-BLAST MACHINE.

No. 914,105.

Specification of Letters Patent.

Patented March 2, 1909.

Application filed June 11, 1908. Serial No. 437,679.

To all whom it may concern:

Be it known that I, FRANCIS P. BOLAND, a citizen of the United States of America, and a resident of Providence, in the county of Providence and State of Rhode Island, have invented certain new and useful Improvements in Sand-Blast Machines, of which the following is a specification.

This invention relates to improvements in sand-blast machines, so-called, and it consists in the novel construction and combination of parts arranged to produce a continuous blast or working effect with a greater degree of efficiency than is obtainable in machines of this class heretofore devised.

The improved machine is simple in construction and comparatively inexpensive to manufacture, all as more fully hereinafter set forth and claimed.

In the accompanying sheet of drawings, Figure 1 represents a side elevation, in partial section, of a sand-blast machine embodying my improvements, and Fig. 2 is a vertical longitudinal sectional view, in enlarged scale, taken through the center of the auxiliary sand holder and the air-blast connection; the several parts being represented in the normal operative position or relation.

The following is a more detailed description of a sand-blast machine provided with my improvements: The head or body portion of the machine is supported by legs *l* and provided with what may be termed the operating or working chamber *a* having transparent sides. The front side is provided with a swinging door *c* capable of being opened and closed. A perforated horizontal partition or work-supporting plate *i* separates the chamber proper from the main hopper or sand reservoir *e* beneath, from which latter is supplied the sand or abrading material employed in the machine. The rear side of the chamber *a* is in continuous open communication with the upwardly inclined hollow extension *f* which terminates at the top in the enlarged exhaust outlet *g* communicating with the outer air. The top portion of the head member may have a pyramidal form, as indicated at *a'*. The said front side is also provided with an outwardly extending guard or protector *b* disposed with respect to the usual hand-holes *d* and located below said door *c*.

The present invention resides more particularly in combining the sand and air blast in a novel manner at or below the hopper

and conducting the thus acted upon sand upwardly therefrom unobstructedly to the discharge-nozzle *u*.

A vertically arranged small cylindrical auxiliary holder *s* having a chamber *r* is as drawn located below the hopper and being in direct communication therewith via pipe *m* and the interposed valve or cock *m'*; the latter being employed for controlling the flow of sand from the hopper. The lower portion *s'* of the said member *s* is beveled and provided with a fitting or end *h* tapped to receive the tubular end of an elbow member *t*; the latter in turn arranged to receive air under pressure from a suitable air-supply or blower via pipe *t*. The said member *t* is reduced in diameter to form a nozzle *t*², the same extending upwardly through the bottom of the holder *s* a short distance.

A circulating-pipe *u* passes downwardly through the movable top or cover *s'* of the holder *s* and is positioned so as to form at the bottom an annular space *t*⁴ between the former and said nozzle *t*², and at the same time having the part of the pipe adjacent the latter provided with perforations *p*. The circulating-pipe passes upwardly through a lateral recess *f'* of said extension *f* and is bent to a comparatively large semi-circular form and terminates in the downwardly open discharge-nozzle *u*². As thus devised and shown the circulating-pipe is unobstructed throughout its entire length, except at the usual discharge-nozzle, since no branch pipes and valves are connected with or joined to it, the result being that a greater degree of efficiency and economy are attained.

In operation air under suitable force or pressure flows via pipe *t* and bore *t*³ of the elbow or fitting *t* directly into the lower end portion of the circulating-pipe *u* and produces an upward draft or current in the latter, the result being to suck the sand (flowing by gravity from the open hopper into the chamber *r* of the holder *s*) through the apertures or perforations *p* into the annular space *t*⁴; the thus combined or associated air and sand pass upwardly and unobstructedly through pipe *u* and are discharged from the main nozzle *u*²; the force of the thus ejected sand being employed for abrading the surfaces of articles of metal or other material held thereunder.

While I have stated that the upward draft of the air issuing from the nozzle *t*² operates to suck the sand into the annular space *t*⁴ and

to then force it upwardly therefrom in the feed-pipe u to the place of its discharge, it is also true that the sand will flow by gravity into said annular space and fill the same to the level of the upper perforation if a sufficient head of sand be contained in the chamber r .

I am aware that it has been proposed to introduce a jet of air directly into a mass of sand at the bottom of a reservoir so as to agitate the sand preparatory to or in conjunction with the action of the air-blast proper located at or near the discharge-nozzle of the circulating or feed-pipe and forming a mixing chamber at that point. As thus devised the loosened sand is drawn upwardly into the said chamber by the main air-blast introduced into the latter.

In my invention the lower end of the feed-pipe u is continuously open and extends a short distance below the continuously open discharge-end of the air-nozzle t^2 , thus producing an annular space which is kept filled with the sand, the latter, however, not over-flowing into the air-nozzle as in the case of a fluid. If desired means may be employed for regulating the flow of sand from the hopper into the said annular space, and also means, as a cock g^1 , for controlling the volume of air-supply issuing from the air-nozzle.

I do not desire to limit my invention to the precise or exact construction and arrange-

ment of parts as shown and described herein as changes or modifications of the device 35 may be made therein without departing from the spirit or scope of the invention.

I claim as my invention and desire to secure by United States Letters Patent,—

In a sand-blast machine, the combination 40 with the casing or body portion provided with a working chamber, a main reservoir for sand located below and being in open communication with said chamber, and an auxiliary reservoir into which sand may flow from 45 the main reservoir by gravity, of an open air-blast inlet-nozzle extending upwardly a short distance through the bottom of said auxiliary reservoir, a main circulating-pipe having its lower portion perforated and surrounding the said inlet-nozzle so as to form 50 an annular space therebetween into which space the sand passes by gravity action, and having the circulating-pipe extending upwardly through the auxiliary reservoir and 55 provided with a return bend terminating in a nozzle arranged to discharge mingled sand and air into said working chamber by the action of the air-blast issuing from said inlet-nozzle, substantially as described.

Signed at Providence, R. I., this 9th day of June, 1908.

FRANCIS P. BOLAND.
